UNITED STATES PATENT OFFICE.

HARRY JAMES JONES, OF SAN ANGELO, TEXAS.

DOORSTOP.

Application filed July 1, 1925. Serial No. 40,907.

This invention relates to retaining devices and has for its general object the provision of a device adapted to be mounted upon a door and operable to hold the door 5 in any desired position so that closing or slamming of the door as the result of drafts will be prevented.

The object of the invention, more specifically stated, is to provide a device of 10 this character embodying a holding lever equipped with spring means operable to retain the lever selectively in operative or inoperative position, the arrangement of the parts being such that shifting from one 15 position to the other may be effected by comparatively light pressure by the operator's foot.

Another object of the invention is to provide a device of this character having a 20 movably mounted anchor member on the spring tension means, the anchor member shifting in accordance with the position of the holding arm or lever so as to be past center with respect to the pivot of the holding member for maintaining the latter in selected position.

Yet another object is the provision of 25 guide means on the frame of the device and on the holding member, the guide means co-operating to prevent bending or other distortion or displacement of the holding member when in use.

The invention further contemplates the 30 provision of a device of this character which consists of the minimum number of parts whereby it will be inexpensive to manufacture, easy to install and also neat in appearance as well as easy to operate, efficient and durable in service, and a general improvement in the art.

To the attainment of the foregoing and other objects and advantages the invention 35 consists in the details of construction and the arrangement and combination of parts 40 to be hereinafter more fully described and claimed and illustrated in the accompanying drawings in which:

Figure 1 is a fragmentary elevation of the 45 lower portion of a door and its jamb showing the invention applied and in inoperative or released position.

Figure 2 is a similar view with the door 50 slightly open, showing the device in operative or floor engaging position.

Figure 3 is an elevation of the rear side 55 of the device,

Figure 4 is a detail section taken substantially on the line 4—4 of Figure 3,

Figure 5 is a detail section taken on substantially the line 5—5 of Figure 1, and 60

Figure 6 is a detail section through the floor engaging cup.

Referring more particularly to the drawings, the letter A designates a door cooper- 65 ating with a jamb B, and C represents the floor on which is mounted the door sill D located within the lower opening.

In carrying out the invention I provide a frame 10 of any desired size, shape and material, finished or treated in any preferred manner to have a neat and attractive appearance. In the present instance this frame is represented as being of elongated 70 rectangular form with the corners rounded and formed with suitable holes 11 through which are passed screws 12 or the like whereby the frame may be secured upon the door near the lower edge thereof. The end portions of this frame are formed with openings 13 and 14, the former of which has its outermost edge 15 curved and the latter of which has its inner edge 16 curved and formed with a projection 17 for a purpose to be described.

The numeral 18 designates the movable 75 floor engaging arm or lever which may conveniently be formed either as a casting or stamping and which is of elongated forma- 80 tion preferably channel shaped in cross sec- 85 tion as clearly indicated in Figure 5. In- 90 termediate its ends this member 18 is formed with a lug or ear 19 disposed against the outer side of the intermediate portion of the frame and pivoted thereto as by a bolt, rivet or the like indicated at 20. The above de- 95 scribed curved edges 15 and 16 of the open- 100 ings in the frame are struck from the pivot point 20 as a center. At its ends the mov- 105 able member 18 is formed or otherwise pro- 110 vided with upstanding projections 21 and 22 which have their upper surfaces pre- 115 ferably ridged or toothed as shown to avoid slipping when engaged by the operator's foot during the act of moving the member 18 into one position or the other.

Mounted at one end of the member 18 is the floor engaging element 23 formed prefer- 120 ably as a cup of rubber held in position in any desired manner as for instance by means of a screw 24 threaded into the member 18 125 and passing preferably through a washer 25 within the cup. This member 23 is designed

to bear upon the surface of the floor when the device is in operative position and it will be noted that it will have a sort of suction cup action insuring a firm hold on the floor.

5. To apply the necessary tension to the member 18 for holding it in operative position and also for holding it in released position, I employ an elongated coil spring 26 of any desired strength, which spring 10 has one end connected with a transverse pin 27 or the like extending through the member 18. The other end of the spring is connected with a lateral lug 28 on the free end of an arm 29 pivoted on the bolt 20. 15 The lug 28 is disposed outwardly of and in slightly spaced relation to the curved edge 16 of the opening 14 and is engageable with the projection 17 which serves as a stop for limiting movement of the arm 29 in one 20 direction. Movement in the other direction is limited by engagement of the lug 28 with the upper edge of the opening 14. To accommodate the lug 28 the member 18 may have its side toward the frame notched as 25 shown at 30.

At the curved edge 15 of the opening 13 is provided a flange 31 engaged by an overhanging hook 32 on the member 18, this detailed construction being of importance in 30 that bending or displacement of the member 18 with respect to the frame will be prevented. Furthermore the flange 31 and hook 32 coact to define guide means for the member 18 throughout its movement in 35 either possible direction.

Assuming that the device has been constructed, assembled and applied to a door, it will be seen that when the device is in inoperative position the parts are arranged 40 as in Figure 1, the member 18 being then in substantially horizontal position and maintained so by the spring. At such a time the suction cup is of course out of engagement with the floor and the door may be moved 45 freely in the ordinary manner. At this time the arm 29 is in its uppermost or upwardly swung position with the lug 28 engaging against the upper edge of the opening 14. When the arm is in this position the spring 50 lies above the pivot bolt 20 and its tension acts to maintain the member 18 in its horizontal position.

To render the device operative, it is merely necessary for the operator to press his foot 55 upon the projection 22 and force this end of the member 18 downwardly. During this movement the tension of the spring upon the arm 29 will cause the latter to swing downwardly into the position shown in Figure 2, the lug 28 engaging against the projection 17. The shifting of the position 60 of the arm 29 results in bringing the spring to a position entirely below the pivot 20 so that the tension of the spring will hold the 65 suction cup 23 in firm engagement with the

floor. Obviously the door will then be held against movement so that it cannot be blown or otherwise accidentally moved. This is of course a great advantage in that slamming of the door will be positively prevented and 70 in the case of glass doors this is of obvious importance as breakage of the glass will be avoided.

Attention is directed to the fact that there is only one moving part at the front of the 75 frame, the frame being peripherally flanged as shown so as to define a species of housing within which the arm 29 operates while concealed from view. When the member 18 is in its inoperative or horizontal position it 80 serves as a housing for the spring which is almost entirely enclosed therein, as shown in Figure 1. For the sake of lightness the frame may be of an extremely skeleton-like form, if preferred, though this is a matter 85 which may be varied to meet the wishes of the manufacturer.

While I have shown and described the preferred embodiment of the invention, it should be understood that the disclosure is 90 merely illustrative as I reserve the right to make all such changes in the details and arrangement of parts as will not depart from the spirit of the invention or the scope of the subjoined claims. 95

Having thus described the invention, I claim:

1. A door stop comprising a frame adapted to be mounted upon a door at the lower portion thereof, a member pivoted intermediate its ends upon the frame and equipped at one end with a friction element engageable with the floor, a spring connected at one end with said end of said member, and an automatically shiftable anchor member 105 for the other end of the spring. 100

2. A door stop comprising a frame adapted to be mounted upon a door at the lower portion thereof, a member pivoted intermediate its ends upon the frame and equipped at one end with a friction element engageable with the floor, a spring connected at one end with said end of said member, an automatically shiftable anchor member for the other end of the spring, and coacting 110 guide elements on the frame and said first-named member for guiding the latter during its movement and preventing lateral movement thereof with respect to the frame. 115

3. In a door holding device, a frame adapted to be mounted on the lower portion of a door, an elongated lever pivoted intermediate its ends upon the frame, a friction element on one end of said member engageable with the floor, an arm pivoted on the 120 frame, and a spring connected at one end with said arm and having its other end connected with said end of the lever. 125

4. In a door holding device, a frame adapted to be mounted on the lower portion 130

of a door, an elongated lever pivoted intermediate its ends upon the frame, a friction element on one end of said member engageable with the floor, an arm pivoted on the frame, a spring connected at one end with said arm and having its other end connected with said end of the lever, and stop means on the frame for limiting swinging movement of said arm in both directions.

5 10 5. A device of the character described comprising a support adapted to be mounted upon the lower portion of a door, an elongated lever pivoted intermediate its ends upon the support, a friction element on one end of the lever engageable with the floor, projections on both ends of said lever serving as pressure receiving portions, an arm pivoted on the support at said pivot for the lever, and a spring connected with the first-named end of the lever and with said arm.

15 20 6. A device of the character described comprising a support adapted to be mounted upon the lower portion of a door, an elongated lever pivoted intermediate its ends upon the support, a friction element on one end of the lever engageable with the floor, projections on both ends of said lever serv-

ing as pressure receiving portions, an arm pivoted on the support at said pivot for the lever, a spring connected with the first-named end of the lever and with said arm, the support having an opening in one end thereof with a curved edge concentric with said pivot, and a guide hook on the lever overhanging said edge.

25 30 35 40 45 50 7. A device of the character described comprising a support adapted to be mounted upon the lower portion of a door, an elongated lever pivoted intermediate its ends upon the support, a friction element on one end of the lever engageable with the floor, projections on both ends of said lever serving as pressure receiving portions, an arm pivoted on the support at said pivot for the lever, a spring connected with the first-named end of the lever and with said arm, the support having an opening at one end thereof with a curved edge concentric with said pivot, and said arm having a lateral lug extending through the opening at said curved edge and to which the spring is attached.

In testimony whereof I affix my signature.

HARRY JAMES JONES.
